PATENTED MAY 10 1870

Fig. 2.

Hans Christian Heistad

United States Patent Office.

HANS CHRISTIAN HEISTAD, OF BROOKLYN, NEW YORK.

Design No. 4,014, dated May 10, 1870.

DESIGN FOR A CALENDAR.

The Schedule referred to in these Letters Patent and making part of the same.

To all whom it may concern:

Be it known that I, HANS CHRISTIAN HEISTAD, of Brooklyn, in the county of Kings and State of New York, have invented or produced a new and original Design for a Calendar, and the following is declared to be a correct description of the same.

This calendar is for showing the days of the week and of the month; also about the average time of the rising and setting of the sun during the month.

In the drawing—

Figure 1 is a plan, and

Figure 2 is an elevation of said calendar.

The design of the shape and configuration of this calendar is as follows:

The case *a*, containing the dials with marks and numbers, is round, and in the center is an ornamental three-part knob, to operate the respective disks or dials by a proper connection.

The proper openings are provided in the case *a* for observing the dials.

My ornamental knob is made with the star-leaf ornament *c* forming the lower part of the knob, the concave disk *d* forming the central part of the knob, and the globular ornament *e* forming the upper part of the three-part knob.

The respective portions of this knob are connected by tubular sleeves with the respective dials of the calendar.

I claim as my invention—

The design of the shape and configuration of the calendar and ornamental three-part knob, as described and represented.

Signed this 24th day of March, A. D. 1870.

Witnesses: HANS CHRISTIAN HEISTAD.

CHAS. H. SMITH,
GEO. T. PINCKNEY.
